[57] **CLAIM**

The ornamental design for an adapter for a telephone handset receiver, as shown.

DESCRIPTION

FIG. 1 is a perspective view of an adapter for a telephone handset receiver showing my new design;
FIG. 2 is a right side elevation view thereof, the side opposite being a mirror image; and,
FIG. 3 is a front elevational view thereof.
The broken line showing of portions of a telephone handset is for illustrative purposes only and forms no part of the claimed design.

FIG. 2

FIG. 3
